[57] CLAIM

The ornamental design for a fishing reel handle, as shown
and described.

DESCRIPTION

FIG. 1 is a perspective view of the front, top and one side of
a fishing reel handle according to a first embodiment show-
ing our new design;

FIG. 2 is a front elevational view thereof;

FIG. 3 is a top plan view thereof;

FIG. 4 is a side elevational view of said one side thereof, the
opposite side being a mirror image thereof;

FIG. 5 is a bottom plan view thereof;

FIG. 6 is a rear elevational view thereof;

FIG. 7 is another top plan view, the broken line showing of
environment is for illustrative purposes only and forms no
part of claimed design;FIG. 8 is a perspective view of the top, front and one side of
a fishing reel handle according to a second embodiment
showing our new design;

FIG. 9 is a front elevational view thereof;

FIG. 10 is a top plan view thereof;

FIG. 11 is a side elevational view of said one side thereof,
the opposite side being a mirror image thereof;

FIG. 12 is a bottom plan view thereof;

FIG. 13 is a rear elevational view thereof; and,

FIG. 14 is another top plan view, the broken line showing of
environment is for illustrative purposes only and forms no
part of claimed design.
